UNITED STATES PATENT OFFICE.

EDWARD EDSSEN, OF NORTH MILWAUKEE, WISCONSIN.

BURNER-CONTROLLING MEANS.

Application filed July 13, 1925. Serial No. 43,313.

My invention relates to means for controlling the fuel supply of an oil burner, and particularly to that type of burner which is placed within the fire box of a heating furnace adapted for domestic use or the like.

The object of my invention is to provide means that will automatically cut off the flow of fuel to the burner in the event of the extinguishing of the flame or a leaky burner.

A further object of the invention is the provision of means controlled by the leakage from the burner valve, that will cut off the flow of fuel thereto.

It is a further object of my invention to provide means for indicating both visually and audibly when the supply to the burner has been cut off.

A further object of my invention is to provide means that will indicate in various parts of the house or in a central station when a fire breaks out in the building in which my system is used.

In the accompanying drawings.—

The figure shown therein is a detail view showing the different parts essential in the operation of the device.

Referring to the drawings in detail, the numeral 1 designates the furnace of a heating system or the like, in the fire box of which is placed the liquid fuel burner 2, same having the fuel controlling valve 3, arranged within the supply line, and being operated by a chain or the like passing around a pulley arranged on the valve stem and a second pulley mounted for actuation in any part of the building in which the device is installed and preferably in the room above.

The fuel for the burner is retained in the fuel supply tank 4 and under suitable air pressure. The tank 4 has connected thereto the pipe lines 5 and 6, the former leading to a pump 7 and the latter connecting the former adjacent the pump. The line 5 has arranged therein adjacent the connection of the line 6, a valve 8, while the line 6, has adjacent its connection with the line 5 a valve 9, the purpose of which will be described more fully hereinafter. Also arranged in the pipe line 5, between the pump and the connection of the line 6, is a check valve 10, the purpose of which will be apparent as the description proceeds.

Leading from a suitable underground auxiliary fuel storage tank to the pump 7, is

a pipe line 11, same having therein the valve 12 and the check valve 13, between which is connected a pipe 14 which leads to the atmosphere and having therein the valve 15. 60

The pipe line 6 has connected thereto the branch pipe 16 which leads to the burner 2 and this pipe has arranged therein the automatically operated valve 17.

From the above description, it will be apparent that the operation of the means for conveying fuel to the burner is as follows: Assuming that the supply tank 4 is empty and it is desired to transfer fuel from the storage tank to the supply tank, the operator closes valves 8 and 15, and opens valves 9 and 12, the pump 7 is then operated and fuel will be raised from the storage tank to the supply tank 4 until the desired amount therein is indicated by the gage 18 arranged 70 on one end of the tank. After the desired amount of fuel has been placed in the tank 4, it is then necessary to place same under pressure, and this is done by closing valves 9 and 12, and opening valves 8 and 15, after 75 which the pump is operated and air is drawn in from the atmosphere through the pipe 14 and forced into the tank 4 by the pump.

In order to insure the proper pressure within the tank 4, I have arranged in the pipe line 5, adjacent the tank 4 suitable pressure indicating gages 19 and 20, one of which is placed within the room above, while the other serves as an indicator within the basement. When it is desired to pass the fuel 90 to the burner 2, the valves 17 and 3 are opened and the latter regulated by the operator as desired.

The controlling means for the fuel supply to the burner is as follows: The burner 3 has pivotally mounted thereto the bar 21, one end of which has set therein the cup 22 arranged to receive the drip from the control valve 3 of the burner. The cup 22 is held adjacent the valve 3 by a weight 23 carried at the other end of the pivotal bar 21. Pivotally mounted upon the base of the burner and adapted to engage the lug 24 on the bar 22 is an upright lever 25, same being normally held against the lug by the spring 25'. The lever 25 has connected thereto a cord or cable 26 which passes around a pulley 27 arranged in any convenient place adjacent the burner.

Arranged upon the ceiling of the basement is a bracket member having mounted therein the pulley 28, and pivotally mounted

to the bracket the arm 29, one end of which has mounted therein the pulley 30 around which the cord 26 passes from the pulley 27. The free end of the cord 26 is passed around 5 the pulley 30' and then connected to the bar 31 supported from the ceiling by the fusible links 32. The bar 31 has also connected thereto the weight 33.

Passing around the pulley 28 is a cable 34, 10 one end of which is connected to the valve 17, while the other end has connected thereto the weight 35.

The pulley 28 has arranged on one side thereof a pin 36 adapted to engage a lug 15 37 carried by the pivoted arm 29 and the lug being held in engagement thereto by the weight 38 on the end of the arm.

The operation of the fuel control is as follows. Leakage from the valve 3 drops 20 into the cup 22, which causes the bar 21 to rock and release the lever 25, the same being pulled over by the spring 25', and pulling upon the cord 26, thereby releasing the lug 37 from the pin 35 and allowing the weight 25 35 to drop, thus closing the valve 17.

In the event of a fire, the links 32 are broken by the heat, thus causing the weight 33 to drop, thus pulling on the cord 26 and releasing the weight 35 which closes the 30 valve 17 and cuts off the flow of the fuel to the burner.

The means for indicating when the burner has ceased operation, or when a fire breaks out in the basement consists of a signal 39 35 pivotally mounted within the room above, and moved to a position as indicated by the dotted lines when the arm 29 is caused to drop by the controlling means, the signal being connected to the arm by a cable 40. The indicating means consist further of an 40 electric circuit having therein a number of bells 41 and the lamps 42 positioned in various parts of the house or elsewhere if desired. The circuit is normally held open 45 by the coiled spring 39' and when the weight 33 drops the main switch 43 of the electric circuit is thrown in an operative position by the movement of the cord 34, same oper-

ating the switch 43 by the engagement of the button 44 carried by the cord 34 with one 50 arm of the switch.

From the foregoing, it is thought that the construction, operation and many advantages of the herein described invention will be apparent to those skilled in the art 55 without further description, and it will be understood that various changes in the size, shape, proportion and minor details of construction, may be resorted to without departing from the spirit or sacrificing any of 60 the advantages of the invention.

Attention is directed to the fact that the furnace, as indicated at 1, is provided with a sectional fire brick or clay core having a series of radial flues *a* extending therethrough, whereby the heat is caused to travel through the fire clay and thus superheat the same to a higher degree to increase the efficiency of the heating unit as a whole. The fire clay core is preferably formed in 70 radial sections so that they can be quickly dropped into place and removed for repair purposes.

Having thus fully described my invention, what I claim as new, and desire to secure by 75 Letters Patent, is:—

In a system of the character set forth, the combination of a liquid fuel burner and a controlling valve therefor, a bar pivotally mounted to the burner and having a drip 80 receiving cup on one end held adjacent the burner, a lever pivotally mounted to the burner and actuated by the movement of the bar, a weight for closing said fuel valve and being connected thereto by a cable, said cable being supported by a normally locked pulley, means for releasing said pulley and permitting the closing of the valve, said means being actuated by the movement of the lever. 90

In testimony that I claim the foregoing I have hereunto set my hand at Milwaukee, in the county of Milwaukee and State of Wisconsin.

EDWARD EDSEN.
